UNITED STATES PATENT OFFICE.

JAMES C. KELLEY, OF LEONARDVILLE, KANSAS.

HEAD-GEAR FOR VEHICLES.

SPECIFICATION forming part of Letters Patent No. 395,237, dated December 25, 1888.

Application filed November 21, 1887. Serial No. 255,733. (No model.)

To all whom it may concern:

Be it known that I, JAMES C. KELLEY, a citizen of the United States, and a resident of Leonardville, in the county of Riley and State 5 of Kansas, have invented certain new and useful Improvements in Head-Gear for Vehicles; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a rear perspective view of my 15 new and improved head-gear for vehicles. Fig. 2 is a vertical sectional view of the same, and Fig. 3 is a perspective detail view of the extension of the reach.

Similar letters of reference denote corresponding parts in the several figures.

My invention has relation to head-gear for vehicles; and it consists in the peculiar construction and combination of the several parts of the same, as will be hereinafter fully set 25 forth.

In the accompanying drawings, the letter A indicates the fifth-wheel, consisting of two segments, which I will designate, for convenience of reference, as the "upper" and "lower" 30 segments, B and C, respectively. The upper segment, B, is struck out from a single piece of sheet or plate metal, and consists of the transverse bearing-plate D, having therewith the clip-arms E, which are fastened to the head-block F of a vehicle by their upper reduced ends projecting through slots or apertures in tie-plates G, and bent or flanged, as seen at H, so as to prevent them from becoming detached from the said tie-plates. The 35 outer edge of this segment B is flanged, as shown at I, which serves as a dust-guard for the lower segment, C, and the segment is further provided with a lip or projection, B'. The lower half or segment of the fifth-wheel 40 is provided with similarly-constructed clip-arms J and tie-plates K, and is secured in substantially the same manner as the upper segment, with the exception of one pair of clip-arms, which are secured by means of a 45 rearwardly-curved tie-plate, L, the rear reduced and rounded end of which projects

through a slot in its straight flat portion, or, in other words, that portion which bears against the under side of the axle, and is bent or flanged, as shown at M, to prevent it from 55 becoming detached. The transverse bearing-plates of the segments are formed at their intermediate portions with cone-bearings N and O, through which a king-bolt, P, which is seated with its countersunk head in the cone-bearing of the lower segment, projects with its shank portion through the cone of the upper segment, and thence through the head-block of the vehicle, where it is secured. By thus securing the king-bolt and forming the 60 transverse bearing-plates of the segments with cone-bearings I obtain a smooth and strong pivot-joint, and at the same time dispense with the trouble of boring a hole through the axle-tree, as is commonly done. 65

Q indicates the reach-socket, struck from a single piece of sheet or plate metal and formed with a hollow cylindrical body portion, Q', the forward end of which is suitably secured to the king-bolt and the head-block of the vehicle, 70 while the rear lower end terminates in a downwardly and forwardly curved brace or support, Q², the free end of which is pivoted to turn laterally on the reduced and rounded portion of the curved tie-plate L, while the 75 upper portion, Q³, is parallel with the body of the cylindrical socket Q, and is secured to the said body and to the lip upon the inner edge of the upper segment by means of a rivet or any other suitable fastening device, thus 80 forming a strong support for the fifth-wheel and the reach-socket, and at the same time forming a guide for the lower segment. On the under side of this reach-socket is a transverse elongated aperture, Q⁴, the object of 85 which will be hereinafter fully set forth.

R represents the reach-extension, which is secured to the forward end of the reach. This extension is formed with a solid cylindrical body portion at its forward end, which is swiveled in the socket Q by a round nut or projection, Q⁵, secured to its end, which is afterward struck up, as shown at R', to prevent the nut from working off, while its rear portion is coned and then formed with long and 90 short flat wings or strips R² and R³, respectively, by which the extension proper is se- 95

cured to the reach; but should it be desired to attach this extension to a vehicle employing two reaches the long side wings or strips are bent outwardly and are secured to the 5 sides of the reaches, the beveled meeting ends of which are secured together at their upper and lower sides by the short strips or wings.

A stop-bolt, T, is secured to the reach-extension near its forward end, and its head 10 projects through and plays laterally in the elongated aperture Q⁴ in the reach-socket. This will prevent the vehicle from upsetting, but will at the same time give ample room for it to rock side to side.

15 It will be seen that by swiveling the reach to the head-block there will be no strain upon the fifth-wheel, and also will permit the running-gear of the vehicle to travel over rough or uneven ground without jarring the contents of the vehicle to as great an extent as would be the case with vehicles employing the rigid or stationary reach.

It will be seen that by constructing the several different parts of my invention of plate 25 or sheet metal in the manner herein described the expense is greatly reduced; and it will further be seen by the novel way of connecting the several parts together bolts and nuts are dispensed with, which overcomes the great 30 difficulty hereinbefore experienced by the heads of the bolts wearing away or by the nuts working loose or dropping off, causing the several parts to become loose and rattle or become entirely detached.

35 Having thus described my invention, I claim and desire to secure by Letters Patent of the United States—

1. In a head-gear for vehicles, the combination of the fifth-wheel, consisting of segments, 40 each of which consists of a transverse bear-

ing-plate formed with a cone-bearing and clip-arms struck out from a single piece of sheet or plate metal, a rearward curved plate having the rounded and reduced end secured to the intermediate clip-arms of the transverse 45 bearing-plate of the lower segment, the reach-socket struck out from a single piece of plate or sheet metal and formed into the cylindrical shape shown and described, the rear end of which is adapted to be secured to the head-block of a vehicle, and a curved support integral with the other end of said socket and pivoted at its lower end to the reduced and rounded portion of the curved tie-plate.

2. In a head-gear for vehicles, the combination of the fifth-wheel, consisting of segments constructed and struck out in substantially the manner described, a king-bolt, a reach-socket constructed from a single piece of sheet or plate metal, and a curved support integral 50 with the rear end of said socket, the lower end of said support being pivotally connected, while the upper rear straight portion is secured by means of a rivet to the reach-socket, and a reach-extension comprising a cylindrical body portion, the forward end of which is provided with an enlargement or nut and the rear end provided with strips or wings.

3. In a head-gear for vehicles, the combination of a reach-socket, as described, having an elongated aperture in its side, with a reach-extension and a bolt secured thereto and projecting with its head through said aperture.

In testimony that I claim the foregoing as my own I have hereunto affixed my signature 75 in presence of two witnesses.

JAMES C. KELLEY.
